UNITED STATES PATENT OFFICE.

WESLEY REES, OF MEMPHIS, MISSOURI.

DESIGN FOR A PAVING-BRICK.

SPECIFICATION forming part of Design No. 32,646, dated May 8, 1900.

Application filed April 9, 1900. Serial No. 12,258. Term of patent 14 years.

To all whom it may concern:

Be it known that I, WESLEY REES, a citizen of the United States, residing at Memphis, in the county of Scotland and State of Missouri, 5 have invented and produced a new and original Design for a Paving-Brick; and I do hereby declare the following to be a full, clear, and exact description of the same, reference being had to the accompanying drawings, forming a part thereof.

Figure 1 of the drawings is a perspective view of a paving-brick embodying my new design; Fig. 2, a side elevation thereof; Fig. 3, an end view.

15 In the accompanying drawings, A represents the paving-brick constructed in accordance with my design, a rib *a* projecting from one side of the brick and extending longitudinally thereof, and upon the opposite side of the brick is a correspondingly-formed groove *b*, the rib and groove extending throughout

the length thereof. The ends *c* of the brick flare outwardly in a direction from top to bottom, forming thereby a base *d* of increased length, the thickness or width of the brick 25 being uniform from top *e* to bottom *f*, thereby forming a brick of uniform thickness and of increased length at its base, with a longitudinal rib and a longitudinal groove upon its respective sides.

Having now fully described my invention, what I claim as new, and desire to secure by Letters Patent, is—

The design for a paving-brick, substantially as herein shown and described.

35 In testimony whereof I affix my signature in presence of two witnesses.

WESLEY REES.
